UNITED STATES PATENT OFFICE.

SAMUEL SHAW, OF EAST RICHMOND, VICTORIA, AUSTRALIA.

LIGHTING APPLIANCE FOR GAS-LAMPS.

No. 835,117.

Specification of Letters Patent.

Patented Nov. 6, 1906.

Application filed April 5, 1904. Serial No. 201,637.

To all whom it may concern:

Be it known that I, SAMUEL SHAW, a subject of the King of Great Britain, residing at 50 Chestnut street, East Richmond, in the 5 State of Victoria, Australia, have invented certain new and useful Improvements in Lighting Appliances for Gas-Lamps, of which the following is a specification.

This invention provides improvements in 10 fittings or appliances adapted for use in connection with those incandescent gas-lamps in which the illuminating power is raised to a very high degree by the employment in the lamp of a long suction or mixing tube. My 15 appliance enables such lamps to be lighted or extinguished by the turning on or off of a tap that is arranged in a convenient position in the gas-pipe leading to the lamp. Thus a lamp may be set outside in the street, the tap 20 for lighting same being within the building to which the lamp is connected.

In order to make the invention clear, I will proceed to describe same with reference to the accompanying sheet of drawings, in 25 which—

Figure 1 shows vertical section of the appliance fitted to a lamp of the class above mentioned. Fig. 2 shows sectional plan of same, taken on line A A of Fig. 1.

30 I employ a small cylinder *a*, having a shoulder that forms a seat *a*² for a valve and a neck *a'* of less diameter, said neck being screw-threaded externally and covered by a cap *m*, that has perforations *m'*, preferably four. The 35 cylinder *a* screws onto a tube *b'*. The top of the tube *b'* forms a seating for a valve *c*, and the cylinder *a* forms a box for the said valve. The cylinder *a* rests at its base on a flange *b*, formed on the tube *b'*. The valve carries a 40 spindle *c'*, and this spindle extends through a perforated guide-piece *c*², set across the tube *b'*. The tube *b'* is internally threaded at its base *b*⁴ to fit upon the gas-supply pipe *k*. A branch pipe *d* proceeds at right angles from 45 the tube *b'*, the bore of the said pipe being less than that of the tube just described. A small vertical pipe *e*, having an internal bore of about one-sixteenth of an inch in diameter, is carried by the pipe *d*, and a screw-pin *f* is 50 provided to adjust the opening at the base of the said pipe. The top of the tube *e* is made roughly in the form of a valve-seat, the edges being serrated with knife-cuts to allow of leakage of gas when valve is on its seat. 55 Such valve consists of a small steel ball *g*. An exterior vertical tube *h* surrounds the

tube *e* and rests upon the pipe *d*, the top of the tube *h* being formed internally as a seat for the ball-valve and having a perforation. The valve *c* is constructed, preferably, out of 60 a piece of plate metal, and its bulk forms about one-third of a sphere and which may be solid or in form of a cup, and its top may have a broad groove cut across its diameter, so as to prevent the top of the valve when moved 65 upward by a strong pressure of the gas from completely closing in the top of the dome from the gas below; but in practice the valve will not rise to the dome, but will be lifted from its seat sufficiently to allow passage of 70 gas to the burner.

The construction so formed is designed to fit into the lamp of the class above referred to. The cylinder *a*, with the cap *m*, lies within the suction-pipe *l* of such lamp, and the tube 75 *h* lies within an enlarged end or bell *l'* of the small pilot or lighting-tube *l*², that leads to the interior of the burner, to provide for a continuous small light when the main light is extinguished. The base of the tube *b'* rests 80 upon a cup *l*³, that supports the suction or mixing pipe *l* and allows of the admission of air to same. By these means it is possible to readily remove and replace the burners and mixer-tube and the upper end of the pilot- 85 tube together with the mantle.

In operation my invention works as follows: A small by-pass pipe is arranged at the gas-supply cock—say within the room or any other convenient distance from the burner. 90 Through this small supply-tube the gas continually flows past the stop-cock sufficiently to find its way up to and under the small ball-valve *g*, where it escapes or leaks away through the serrated cuts to and up the tube 95 *l*², at the top of which it continuously burns, while the main burner is not alight. When it is desired to light the main burner, the main gas-supply cock is turned on, so as to allow the full supply and pressure of gas to proceed forward under the specially-constructed circular valve *c* of the burner. The pressure of such gas lifts the valve *c* a sufficient height and allows the gas to proceed up to the main burner above, where it is ignited from the 105 small pilot-light hereinbefore referred to. Meanwhile, owing to the increased pressure and volume of gas accumulating at the small ball-valve *g*, the ball will be blown upward against the top of the tube *h*, thus practically 110 extinguishing the small light burning, while the main burner is lighted. The ball-valve,

however, does not close opening so but that there is always a slight leakage of gas sufficient to maintain the small light, while the main burner is alight. The small light at 5 this time will be imperceptible, and the leakage will obviate the liability that would otherwise exist of its being put out or not being lighted when the gas is turned off from the main burner.

10 The perforated cap *m* will prevent any roaring noise as the gas enters the suction-pipe *l* from the cylinder *a* and which is at present an objectionable feature in connection with the use of these lamps where my 15 appliance is not in use.

Having thus described my invention, what I claim, and desire to secure by Letters Patent, is—

20 A burner for incandescent lamps comprising a main-valve casing, a valve therein controlled, as to its opened or closed condition, by the intensity of the gas-pressure; a pilot-

burner device connected with said valve-casing back of the main valve and containing a valve controlled by the intensity of the gas-pressure to open or close it oppositely to the main valve, a bell surrounding said parts and provided with air-inlets, a mixing-tube forming an upward extension of said bell and adapted to carry the mantle, a cap for the 25 main valve-casing having a plurality of discharge-openings discharging upwardly into said mixing-tube and a tube leading from the pilot-valve casing into the mixing-tube and thence upwardly to the ignition-point of the 30 burner.

In testimony whereof I have signed my name to this specification in the presence of two subscribing witnesses.

SAMUEL SHAW.
